(57) **CLAIM**

The ornamental design for a P-trap with cleanout extension, as shown and described.

DESCRIPTION

FIG. 1 is a front perspective view of a first embodiment of a P-trap with cleanout extension.

FIG. 2 is a front elevational view thereof.

FIG. 3 is a rear elevational view thereof.

FIG. 4 is a top plan view thereof.

FIG. 5 is a bottom plan view thereof.

FIG. 6 is a left side elevational view thereof.

FIG. 7 is a right side elevational view thereof.

FIG. 8 is a front perspective view of a second embodiment of a P-trap with cleanout extension.

FIG. 9 is a front elevational view of the P-trap with cleanout extension of FIG. 8.

FIG. 10 is a rear elevational view of the P-trap with cleanout extension of FIG. 8.

FIG. 11 is a top plan view of the P-trap with cleanout extension of FIG. 8.

FIG. 12 is a bottom plan view of the P-trap with cleanout extension of FIG. 8.

FIG. 13 is a left side elevational view of the P-trap with cleanout extension of FIG. 8; and,

FIG. 14 is a right side elevational view of the P-trap with cleanout extension of FIG. 8.

The broken lines shown in the drawings indicate portions of the P-trap with cleanout extension that form no part of the claimed design.

1 Claim, 8 Drawing Sheets
